(57) **CLAIM**

We claim the ornamental design for the storage device housing, as shown and described.

DESCRIPTION

FIG. 1 is a front right perspective view of the storage device housing comprising the present invention;

FIG. 2 is a front view thereof;

FIG. 3 is a right side view thereof;

FIG. 4 is a left side view thereof;

FIG. 5 is a rear view thereof;

FIG. 6 is a top view thereof; and,

FIG. 7 is a bottom view thereof.

Broken lines shown in the drawings illustrate portions of the storage device housing, and form no part of the claimed design.
